PUMP

Robert J. Byroad, Indianapolis, Ind.

Application August 28, 1941, Serial No. 408,591

3 Claims. (Cl. 103—151)

The present invention relates to pumps and is particularly concerned with transfer pumps for handling gasoline, oil, and similar materials which have a deleterious effect upon the parts of standard types of pumps. The primary object of the invention is to provide a novel and improved double acting pump, so constructed as to develop a maximum life in the use for which it is intended.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a side elevation of a pump embodying the present invention, one-half thereof being shown in vertical section;

Fig. 2 is a top plan view thereof;

Fig. 3 is a fragmental horizontal section taken substantially on the lines 3—3 of Fig. 1; and

Fig. 4 is a fragmental illustration of a modified form of construction.

Referring more particularly to Figs. 1 to 3, it will be seen that I have illustrated a pump including a casing element indicated generally by the reference numeral 10 and formed to provide an inlet port 11 leading from the exterior of the casing to an inlet chamber 12. The casing element 10 is further formed to provide two intake chambers 13 and 14, each open at its side remote from the inlet chamber 12. The casing element is formed with a perimetral lip 15 for a purpose later to become apparent.

A port 16 provides communication between the inlet chamber 12 and the intake chamber 13, a spider 17 being preferably press-fitted into the port 16 and being formed to provide a central aperture 18 in which is reciprocably mounted the stem 19 of the check valve 20 adapted to seat on the spider 17 to close the port 16 against fluid flow from the chamber 13 to the chamber 12. A pin 21 extended through the lower end of the stem 19 limits the upward movement of the valve 20 under the influence of fluid flow from the chamber 12 to the chamber 13.

Similarly a port 22 provides communication between the chamber 12 and the chamber 14, a spider 23 being preferably press-fitted into said port 22 and providing a central aperture 24 in which is reciprocably mounted the stem 25 of a valve 26 which seats on the spider 23 to prevent flow from the chamber 14 to the chamber 12. A

pin 27 passing through the stem 25 limits the upward movement of the valve 26 under the influence of fluid flowing from the chamber 12 into the chamber 14.

5 A mating casing element indicated generally by the reference numeral 28 is formed to provide an outlet port 29 which, in the illustrated embodiment of the invention, is axially aligned with the port 11, and which leads from an outlet chamber 30 to the exterior of the casing. The casing element 28 is further formed to provide two discharge chambers 31 and 32 which are open at their sides remote from the chamber 30. The casing element 28 is formed with a perimetral lip 33 adapted to register with the lip 15 of the element 10, whereby the two casing elements can be clamped together by bolts 103 or other suitable fastening means.

10 The casing element 28 is formed with a port 34 providing communication between the chamber 31 and the chamber 30, and a spider 35 is preferably press-fitted in said port, said spider providing a central aperture 36 in which is reciprocably mounted the stem 37 of a check valve 38 adapted to seat upon the spider 35 to prevent fluid flow from the chamber 30 to the chamber 31. A pin 39 passing through the stem 37 limits upward movement of the valve 38 under the influence of fluid flowing from the chamber 31 into the chamber 30. Similarly, the casing element 28 is formed with a port 40 providing communication between the chamber 32 and the chamber 30, a spider 41 being preferably press-fitted in said port 40 and providing a central aperture 42 in which is reciprocably mounted the stem 43 of a check valve 44 adapted to seat on the spider 41 to close the port 40 against fluid flow from the chamber 30 into the chamber 32. A pin 45 passes through the stem 43 to limit upward movement of the valve 44 under the influence of fluid flowing from the chamber 32 into the chamber 30.

15 The elements 10 and 28 are formed with central partitions 46 and 47 respectively which operate, when the entire casing is assembled, to prevent fluid flow between the two sections of the pump.

20 Interposed between the two casing elements 10 and 28, when the pump mechanism is assembled, is a continuous flexible diaphragm 48, generally separating the chambers 13 and 31 and the chambers 14 and 32, but formed with two ports 50 and 51, the port 50 providing controlled communication between the chambers 13 and 31 and the port 51 providing controlled communication

between the chambers 14 and 32. The perimetal portions 49 of the diaphragm 48 are received between, and firmly clamped in place by, the perimetal lips 15 and 33 of the respective casting elements 10 and 28.

Bounding the port 50 and within the chamber 13 there is a sheet metal annulus 52 in contact with one surface of the diaphragm 48; the inner periphery of said annulus 52 being bent out of the general plane of the diaphragm 48 as indicated at 53, and the outer periphery of said annulus being similarly bent out of said plane as indicated at 54. Within the chamber 31 and contacting the opposite surface of the diaphragm 48 is a second sheet metal annulus 55, allochiral with the annulus 52, the inner periphery of said annulus 55 being bent out of the general plane of the diaphragm 48 as at 56 and the outer periphery thereof being similarly bent as at 57. This arrangement, while permitting ready flexure of the diaphragm both inwardly of and outwardly of the portions gripped between the two annuli without the possibility of cutting the diaphragm against sharp edges of metal, nevertheless provides a support for a portion of the diaphragm closely surrounding the port 50, through the medium of which the diaphragm can be shifted to produce a pumping effect. The portion 56 of the annulus 55, being bent in the fashion shown, provides an annular, line-contact seat for a valve later to be described.

Within the chamber 31 is positioned a spider 58, each leg of which is provided with a foot 59 parallel with the diaphragm 48 and with the mid-portion of said spider, which mid-portion is spaced from the plane of the feet 59. Each of the feet 59 is formed with a perforation 60, and a fastening element 61 is projected through each of said perforations, and through both of the annuli 52 and 55 and the diaphragm 48 to receive a clamping element 62, the head of each fastening element engaging the upper surface of a foot 59, and each clamping element engaging the lower surface of the annulus 52. In the present illustration, I have shown the fastening elements 61 as bolts and clamping elements 62 as nuts threaded thereon; but it will be obvious that any other suitable form of fastening means may be used in place thereof, the requisite being that the fastening means used shall clamp the annuli and the spider feet against opposite surfaces of the diaphragm.

At its mid-point, the spider is perforated as at 63 to permit the penetration thereof by the end portion 64 of a plunger 65, that portion of the end 64 of the plunger which projects through the spider perforation 63 being preferably surrounded by a weld collar 66 which rigidly secures the plunger 65 to the spider 58, and which performs a further function later to be described. Reciprocably confined between the portion 56 of the annulus 55 and the mid-portion of the spider 58 spaced from the diaphragm 48, is a valve 67 adapted to seat upon the portion 56 of the annulus 55 to close the port 50, and resiliently urged to seated position by a coiled spring 68 confined between said valve 67 and the mid-portion of the spider 58. It will be clearly seen that one end of the spring 68 abuts the valve 67, while the opposite end 69 thereof snugly surrounds the weld collar 66 and abuts the mid-portion of the spider 58, whereby said spring is held against accidental dislodgment.

The casing element 28 is formed with a bore 70 aligned with the perforations 63 of the spider 75

58, and said plunger 65 is reciprocably mounted in said bore, projecting therethrough to the exterior of the casing. A packing gland 71 preferably surrounds the outer portion of the plunger 65.

Very similarly, the port 51 is bounded by a sheet metal annulus 72 having its inner and outer peripheries 73 and 74 bent out of the plane of the diaphragm, and by a similar annulus 75 having its portions 76 and 77 similarly bent out of said plane. A spider 78 similar to the spider 58 has its feet 79 perforated as at 80 for the reception of fastening elements 81, which project through said feet, both annuli, and the diaphragm terminating in clamping means 82. In this instance, I have illustrated headed rivets as the means for securing the annuli and the spider to the diaphragm.

The spider 78 is perforated as at 83 for the reception of the portion 84 of the plunger 85, said portion 84 being secured to the spider by a weld collar 86; and a valve 87 is reciprocably confined between the spider 78 and the annular seat formed by the portion 76 of the annulus 75, a spring 88 abutting said valve 87 and being sleeved on the collar 86 in the manner described hereinabove. The casing element 28 is formed with a bore 90 parallel with the bore 70, in which the plunger 85 is reciprocably mounted, and a packing gland 91 surrounds the outer portion of said plunger 85.

The casing element 28 carries a pair of ears 92 supporting a trunnion 93 upon which is oscillably mounted an operating lever 94. To the outer end of the plunger 65 is secured a fitting 95 to which is pivoted one end of a link 96, the opposite end of said link being pivoted to the end portion 97 of the lever 94. Similarly, a fitting 98 is secured to the outer end of the plunger 85 and the link 99 has one end pivoted to the fitting 98 and its other end pivoted to the portion 100 of the lever 94. Obviously, oscillation of the lever 94 about its pivotal axis 93 will result in opposite reciprocation of the plungers 65 and 85.

The casing element 10 is preferably provided with drain ports 101 normally closed by threaded plugs 102.

It will be obvious that, if the inlet port 11 is connected with a source of fluid (said port being surrounded by a threaded spud 104 to facilitate the attachment of a lead line thereto) and if the lever 94 is swung in a counter-clockwise direction about its pivotal axis 93, that portion of the diaphragm within the chamber 13-31 will be depressed, while that portion of the diaphragm within the chamber 14-32 will be elevated. Depression of the first-mentioned portion of the diaphragm will cause a reduction in the volume of the chamber 13 and an increase in the volume of the chamber 31, whereby fluid in the chamber 13 will be caused to elevate the valve 67 against the tendency of the spring 68 and to flow into the chamber 31. Elevation of the diaphragm portion within the chamber 14-32 will increase the volume of the chamber 14 and decrease the volume of the chamber 32, whereby fluid in the chamber 32 will be caused to elevate the valve 44 and flow into the chamber 30; and whereby a partial vacuum will be created in the chamber 14 to cause fluid in the chamber 12 to elevate the valve 26 and to flow into the chamber 14, whereby, of course, fluid will be caused to flow from the source of supply through the supply line into the chamber 12 to replace the fluid forced into the chamber 14.

If, now, the lever 94 is swung in a clockwise direction about the pivotal axis 93 thereof, the diaphragm portion within the chamber 13-31 will be elevated and the diaphragm portion within the chamber 14-32 will be depressed. Thereby, fluid will be caused to flow from the chamber 12, to elevate the valve 28, and to flow into the chamber 13, fluid in the chamber 31 will be forced past the valve 38 into the chamber 30 to expel therefrom fluid formerly in that chamber through the port 29, and fluid in the chamber 14 will be forced past the valve 87 into the chamber 32.

The material selected for the diaphragm 48 will depend, of course, upon the use to which the pump is to be put; but it is my present belief that, particularly for use in connection with oils, gasoline, and the like, the commercial synthetic product known as "Neoprene" is the best available material.

In Fig. 4, I have shown a fragment of a modified form of casing element 28', in which the outlet port 29' is formed at the side of the outlet chamber 30, instead of at the top thereof.

Because of the use of a diaphragm for varying the volumes of the intake and discharge chambers, in place of a packed piston, there is nothing in my pump corresponding to the piston glands of a reciprocating pump which can damage the efficiency of the pump when dried out. And because my valves 67 and 87 seat upon the line-contact elements 56 and 76, drying out of the valve elements themselves will not materially affect the efficiency of the pump. Consequently, even though my pump may stand idle for relatively long periods, it will operate effectively when it is again put into use.

I claim as my invention:

1. A pump comprising a housing formed to provide an intake chamber and a discharge chamber, a flexible diaphragm separating said chambers, and formed with a port therethrough, a spider bridging said port and secured to said diaphragm within said discharge chamber, the mid-portion of said spider being spaced from said diaphragm, a valve confined within the space between said spider mid-portion and said diaphragm and operable to close said port, a plunger penetrating said spider mid-portion, operatively connected thereto, and projecting into said space, said plunger likewise extending through said discharge chamber to the exterior of said housing, and a coiled spring confined between said valve and said spider, one end of said spring abutting said valve and the other end of said spring enveloping the projecting portion of said plunger and abutting said spider.

2. A pump comprising a housing formed to provide an intake chamber and a discharge chamber, a flexible diaphragm separating said

chambers, and formed with a port therethrough, a spider bridging said port and secured to said diaphragm within said discharge chamber, the mid-portion of said spider being spaced from said diaphragm, a valve confined within the space between said spider mid-portion and said diaphragm and operable to close said port, a plunger penetrating said spider mid-portion and projecting into said space, said plunger likewise extending through said discharge chamber to the exterior of said housing, weld material forming a collar inside said spider surrounding and securing the projecting portion of said plunger to said spider, and a coiled spring confined between said valve and said spider, one end of said spring abutting said valve and the other end of said spring being sleeved on said collar and abutting said collar, whereby said spring is supported against displacement.

3. In a pump, a first casing element formed to provide an inlet chamber and an inlet port leading from outside said casing to said inlet chamber, and two intake chambers open at their sides remote from said inlet chamber, said casing element being formed with two intake ports leading respectively from said inlet chamber to said two intake chambers, check valves associated with said ports to prevent flow from said intake chambers to said inlet chamber, a mating casing element formed to provide an outlet chamber and an outlet port leading from said outlet chamber to the exterior of said casing, and two discharge chambers open at their sides remote from said outlet chamber, said mating casing element being formed with two discharge ports leading respectively from said discharge chambers to said outlet chamber, check valves associated with said discharge ports to prevent flow from said outlet chamber to said discharge chambers, means securing said two casing elements together with their open sides in facing relation, a flexible diaphragm interposed between said casing elements and clamped in place therebetween, said diaphragm being formed with two ports therethrough, and one of said ports being disposed between one intake chamber and its associated discharge chamber while the other of said ports is disposed between the other intake chamber and its associated discharge chamber, spring-pressed valve means associated with each of said ports and operable to prevent fluid flow from either discharge chamber to its associated intake chamber while permitting flow in an opposite direction, and two plungers, each operatively associated with said diaphragm near one of said ports and each projecting through said last-mentioned casing element to the exterior thereof, and means for reciprocating said plungers.

ROBERT J. BYROAD.
